R. L. HORSLEY

BALE TIE BUCKLE

Filed Oct. 4, 1922

Robert L. Horsley
INVENTOR

UNITED STATES PATENT OFFICE.

ROBERT L. HORSLEY, OF MEMPHIS, TENNESSEE.

BALE-TIE BUCKLE.

Application filed October 4, 1922. Serial No. 592,321.

To all whom it may concern:

Be it known that I, ROBERT L. HORSLEY, a citizen of the United States, residing at Memphis, in the county of Shelby and State 5 of Tennessee, have invented certain new and useful Improvements in Bale-Tie Buckles, of which the following is a specification.

My invention relates to bale-tie buckles and has for its object the improvement of 10 buckles used in baling cotton; to provide a buckle which may be used with great ease and speed; a buckle which will hold the applied loops of the band in their proper relative positions.

15 The well-known type of buckle now most generally used on cotton bales has broad seats for the loops of the band upon the band-engaging members, made so in order to provide means for bringing the band 20 loops into the buckle and the band is frequently misplaced by the operator in tying the bale. Also the band loops frequently shift from their proper relative positions on the buckle after the bale is tied and cause a 25 weakening and consequent breakage of the buckle.

Referring to the accompanying drawing, which is made a part of this application, the figure is a front view of my plate metal 30 buckle with broken section of one end of bale tie band attached.

In the different forms my buckle consists of band engaging members 1, supporting side 35 2 integral with members 1, the members 1 being provided near their outer ends with

outleaning inclines 3 upon their inner edges and the members, together with the inclines, constitute the seats of the band loops upon the buckle.

Inclines 3 cause applied band loops to hug 40 supporting side 2 and the wider bands will be stretched more at the points of contact with the inclines, as at 5.

The band seats, as formed, will resist a force tending to shift applied loops of band 45 from their most effective positions on the buckle.

Buckle is applied in the usual manner except that when making the final connection the loop of the band is brought in at 50 the side of the buckle.

My buckle may be made from thick steel wire and other minor changes may be made without departing from the spirit of the invention. 55

What I claim is,—

A bale tie buckle comprising band engaging members and a supporting side bar, said band engaging members leading to an open side and provided with retentive devices 60 near their free ends to prevent lateral displacement of the applied loops of a bale tie band upon the buckle, said retentive devices consisting of oblique outleaning inclines upon the inner edges of said members and 65 near the ends thereof.

In testimony whereof, I set my hand, this the 29th day of September, 1922.

ROBERT L. HORSLEY.
